TURBINE PUMP

George A. Biggs, Springfield, Ohio, assignor to
The James Leffel and Company, Springfield,
Ohio, a corporation of Ohio

Application May 22, 1937, Serial No. 144,148

6 Claims. (Cl. 103—87)

My invention relates to hydraulic turbines, and to turbine pumps.

It is my object to provide a unitary hydraulic turbine which is arranged to operate both as a pump and as a hydraulic turbine, utilizing a common stream of water for the dual purpose of operating the turbine and operating the pump, and of pumping a part of the fluid from the stream. This results in a turbine being used for generating current by driving the generator and the turbine being used to operate a pump, the pump constituting a part of the turbine, and utilizing a part of the head-waters as the fluid to be pumped in some other locality, such as a reservoir.

It is particularly my object to provide a turbine runner in which the outer blades of the runner act as the driving blades of the runner, and inner blades of the runner act as pumping vanes of a pump; and furthermore, it is my object to provide the dividing ring between said blades as the means of separating the pumping fluid and the pumped fluid.

It is my object to provide a gate case in guiding alignment with the partition between the blades, and in alignment with the tube for the pumped water so that the pumping water will be guided without turbulence through its draft tube, and the pumped water will be guided without turbulence through its exit pipe.

It is my object, in this connection, to provide a runner shaft for the turbine which can be used in the usual manner for driving a remotely located generator.

In the drawings:

Figure 1 is a section through the combined turbine and pump, illustrating the connection of the turbine to a generator, and the connection of the pump to a reservoir.

Figure 2 is a vertical cross section of the runner in detail.

Figure 3 is a section on the line 3—3 of Figure 2.

Figure 4 is a section on the line 4—4 of Figure 2.

Figure 5 is a modified view showing in section a combined turbine and pump.

Figure 6 is a perspective of the runner of Figure 5.

Figure 7 is a section through a combined runner and pump, showing another modification.

Figure 8 is a perspective of the runner of Figure 7.

Figure 9 is a section on the line 9—9 of Figure 7.

Figure 10 is a diagrammatic view of a modified

form of control for the turbine pumping unit of my invention.

Figure 11 is a section on the line 11—11 of Figure 10.

Referring to the drawings in detail, I designate the head-waters in the power house head-waters chamber 2, in which is located the combined turbine and pumping unit of my invention. The concrete floor 3 of the chamber 2 is provided with an opening 4, through which projects the draft tube 5 of the turbine. Below the floor 3 is the tail-waters compartment 6, in which are the tail-waters 7. The lower gate casing ring 8 rests on the top flange 9 of the draft tube 5. Bolted thereto is the top gate casing ring and cover 10, which is retained in position by the bolts 11. Between these two rings are the gates 12, which are adjusted in the usual manner by the link 13, which is connected by a pitman 14 to an adjusting ring 15, actuated by the arm 16 and having a rack 17 engaging with a pinion 18 on the shaft 19, which is controlled by the hand wheel 20.

Within this gate casing is the runner, consisting of a hollow hub or partition wall 21, which is arcuate in section and open at the top and bottom to form a passageway 22 therethrough. On the outside of this hollow hub is a plurality of runner buckets 23 on the outer end of which, optionally, is a ring 24. This turbine may be of any desired form or character. The buckets may be adjustable or rigid, as shown. On the inside of the hollow hub is a second hub 25, also having faces that are arcuate in section. The contour of this hub follows generally the inside contour of the hub 21. The two hubs are interconnected by the pumping blades 26. The hub 25 is connected by the runner shaft 27 to suitable mechanism, such as a pulley 28 and belt 29, to a generator 30. The generator may be directly mounted on the runner shaft. If desired, the intermediate thrust bearing 31 may be employed, operating within the lubricant chamber 32. The arrangement of the pumping blades 26 is more fully shown in Figure 3, with respect to the gates 12. The relationship of the buckets 23 and the gates 12 is shown more fully in Figure 4.

The bottom of the hollow hub 21 is arranged in overlapping arrangement, with a stationary pipe 33 through which the water is pumped from the head-waters to a reservoir 34. A check valve 35 may be interposed in the line. These same head-waters serve to rotate the turbine so as to rotate the blades 26, pump the water and turn the shaft 27.

In Figure 5 the turbine runner is of the same

general character, but the water enters on the top of the gate casing 10 and is guided thereto by its own stationary guide vanes 36, which are interposed between the top of the gate casing 10 and its stationary bearing support 37 for the lower end of the runner shaft.

In Figure 7 is shown a modified construction, in which no power is taken off of the top of the runner shaft. A housing 38 incloses the top of the shaft. A suitable thrust bearing 39 is supported within the stationary guide vanes 36 for taking the thrust on the head of the shaft. Below the pumping blades, in a supplementary stationary guide tube 40, are stationary straightening vanes 41 to straighten out the turbulence of the water being pumped. This tube 40 is held in position by exterior straightening vanes 42, which are mounted upon the inner wall of the draft tube 5. In this construction the runner buckets 23 are made without an outer ring and are of the propeller type, as distinguished from the Frances runner type of the previous views. In this construction the lower gate ring 8a is adjustable through the pitman 43. The lugs 44 engage the gates 12 in order to rotate them about their pivotal supports 12a.

In order to provide a control for the pumping operations, I have provided the arrangement shown in Figures 10 and 11. The pitman 43 is connected on a gate-operating shaft 46, which is supported at its lower end by a bearing 47. The upper end is connected by bevel gears 48 and 49 to a motor 50. This motor is supplied with current through the lines 51, 52. A travel limit relay 53 is interposed in the line. This circuit of the wires 51, 52 is closed or opened by the switch 54, which is connected by the cable 55 to a float 56 in the reservoir 34. The counterbalancing weight 57 is provided. The switch is also provided with a weight 58. The end of the switch arm is formed into an eye 59, through which the cable 55 passes. Stops 60 on the cable engage with the walls of the eye 59.

When the float 56 moves the lever in one direction, it closes the electric circuit so that the motor will move the gates to closed position, and when the water runs out of the reservoir 34 the float will move to throw the circuit to the position to reverse the motor to open the gates. The travel limit relay 53 effects this reversal.

It will be understood that the difference in level between the top of the head-waters and the top of the tail-waters, 1 and 1 respectively, produces the power desired. Some of this power is used to elevate the water passing through the pump to a higher elevation than in the reservoir 34. The power required to pump a relatively small quantity of water is less than the power that the turbine develops. Therefore, this excess amount, over and above the pumping requirements, can be transmitted to the generator 30. The arrangement shown is purely typical, and it is understood that various other arrangements of my invention may be made. The thrust bearing 31 supports the revolving load of rotating parts, together with the hydraulic thrust of the runner. It will be noted that the vanes of the runner are shaped differently for the turbine and the pump, as shown in Figures 3 and 4, the angle P being the proper degree to suit the pumping requirements and the turbine requirements. Any suitable seal may be provided at the juncture at the bottom of the hollow hub and the pipe through which the water is being pumped.

75 It will be understood that I desire to compre-

hend within my invention such modifications as come within the scope of the claims and the invention.

Having thus fully described my invention, what I claim as new and desire to secure by Letters 5 Patent, is:

1. In combination, a draft tube, a gate casing, gates therein, said gate casing having a top member extending downwardly interiorly of the gates, means mounted on the interior of the top member of said gate casing for supporting a runner bearing, a runner shaft and bearing supported therein, a hub on said shaft, pumping blades on said hub arranged beneath said top member of the gate casing, a ring on said blades in alignment with the top member of the gate casing, and turbine blades on the exterior of said ring.

2. In combination, a draft tube, a gate casing, gates therein, said gate casing having a top member extending downwardly interiorly of the gates, means mounted on the interior of the top member of said gate casing for supporting a runner bearing, a runner shaft and bearing supported therein, a hub on said shaft, pumping blades on said hub arranged beneath said top member of the gate casing, a ring on said blades in alignment with the top member of the gate casing, turbine blades on the exterior of said ring, and a pipe for pumped fluid supported on said draft tube beneath said ring supporting the turbine 30 blades.

3. In combination, a draft tube, a gate casing, gates therein, said gate casing having a top member extending downwardly interiorly of the gates, means mounted on the interior of the top member of said gate casing for supporting a runner bearing, a runner shaft and bearing supported therein, a hub on said shaft, pumping blades on said hub arranged beneath said top member of the gate casing, a ring on said blades in alignment with the top member of the gate casing, turbine blades on the exterior of said ring, and a pipe for pumped fluid supported on said draft tube beneath said ring supporting the turbine 40 blades, and a bearing for said runner shaft 45 mounted within said pumping tube.

4. In combination, a draft tube, a pumped water tube supported therein by water straightening vanes, water straightening vanes within said water tube carrying a bearing, a runner shaft mounted in said bearing, a hub on said shaft, pumping blades on said hub, a ring in alignment with said tube mounted on said blades, runner blades mounted on said ring extending to a point adjacent the draft tube, and means comprising a gate casing adapted to guide water over said runner blades and over said pumping blades in and outside of said ring and adapted also to support the upper end of said runner shaft.

5. In combination, a draft tube, a gate casing with gates therebetween, a turbine runner comprising a hollow hub, the walls of which are in alignment with a downwardly extending extension of the top of the gate casing, a pipe supported within the draft tube in alignment with the bottom of the hollow hub, a second hub and runner shaft, pumping blades connecting the second hub to the interior of the hollow hub, runner blades on the exterior of the hollow hub, a set of stationary vanes mounted on top of the 70 gate casing, and a bearing carried thereby for engaging and supporting said runner shaft, said bearing being submerged beneath the head-waters flowing thereover through said hollow hub.

6. In combination in a combined hydraulic tur- 75

bine and hydraulic pump, a gate casing comprising an upper ring and a lower ring, adjustable gates therebetween, a draft tube associated with the lower gate ring, a hollow hub runner wall associated with an extension of the upper gate ring, a stationary tube for pumped fluid connected to and in extension of said hollow hub arranged concentrically of said draft tube, turbine runner blades on said hub in the space be-

tween it and the gate rings and draft tube, pumping blades on the inside of said hollow hub whereby the fluid flowing over the turbine blades is controlled by said gates while the fluid flowing over the pumping blades is uncontrolled in amount and is pumped through the pipe concentric with the draft tube below the hollow hub. 5
